[57] CLAIM

The ornamental design for a lure transfer assembly, as shown and described.

DESCRIPTION

FIG. 1 is a side elevational view of the lure transfer assembly of the present invention.

FIG. 2 is a top plan view of the apparatus of FIG. 1.

FIG. 3 is a bottom plan view of the apparatus of FIG. 1.

FIG. 4 is a view of one end of the apparatus of FIG. 1.

FIG. 5 is a view of the other end of the apparatus of FIG. 1.

The broken lines showing the lure and line in FIG. 1 are for illustrative purposes only and form no part of the claimed article.
